UNITED STATES PATENT OFFICE.

CHARLES A. STERLING, OF EAST ORANGE, NEW JERSEY.

CURTAIN-FIXTURE.

1,026,286.

Specification of Letters Patent.

Patented May 14, 1912.

Application filed April 29, 1911. Serial No. 624,204.

To all whom it may concern:

Be it known that I, CHARLES A. STERLING, a citizen of the United States, and resident of East Orange, county of Essex, and State of New Jersey, have made a new and useful Invention in Curtain-Fixtures, of which the following is a specification.

My invention is directed to fixtures designed for use with spring controlled roller curtains, such as are ordinarily found in railway cars, cabs, and public conveyances generally, where it becomes necessary to remove the curtains entirely from the window, either to clean the windows, the curtains themselves, or to effect repairs upon the curtains or the fixtures; and to this end it relates particularly to the holding and controlling means by which such curtains are raised or lowered and left locked or held in any desired position, and it has for its objects, first, to provide cheap, simple, and efficient means of the nature referred to which will always act to positively hold the curtain in any desired position and will enable the person manipulating the curtain to do so with the least possible effort, such effort being practically the same in each direction. Second, to provide a fixture of this nature which will always operate when the user attempts to either raise or lower the curtain, no particular care being required to either raise or lower the same, the nature of the fixture being such that no matter how the user may grasp the curtain rod or stick and apply the necessary force to raise or lower the same it will never stick or bind. Third, to provide a fixture of the nature referred to which will permit of quick and easy removal of the curtain when it is desired to detach it from the window. Fourth, to provide a fixture of this nature which will prevent any possibility of breaking or damaging the parts thereof, either when in use in raising or lowering the curtain, or when attempting to detach the curtain and the fixture from the window. Fifth, to provide a fixture of the nature referred to which shall be practically self righting under all conditions of usage. Sixth, to provide a fixture of the nature referred to which will adapt it for use in any window, at all times, no matter what the temperature or climatic conditions may be, the improved fixture being of such a nature as to make it always prac-

tical and with the same degree of nicely of action when properly adjusted. Seyenth, to provide a fixture of the nature referred to which embraces a minimum number of parts, all so constructed as to adapt all of the parts to be placed in position within the casings of the window and in the lower end of the curtain at the least possible expense and with the parts in such definite relation to each other that a certainty of operation is always assured, when the fixture has been properly adjusted and applied, the adjustable features being of such a nature as to adapt the use of my novel invention in windows of variable size, or windows in which the angular relations of the casings may vary materially from right angles with the top and sill thereof and still permit of the use of my novel fixture with the best possible practical results.

Prior to my invention there have been devices put into practical use of a number of types of fixtures for performing the functions for which my invention was devised, but so far as I am aware none as yet have been devised which will comply fully with all of the requirements hereinbefore mentioned. Among these types may be enumerated—first, a fixture in which there are provided spring pressed pawls in opposite ends of a hollow curtain rod or stick adapted to have frictional relations respectively either with the backs of grooves in the window casings in which they move; or with pawls acting in a rack in such grooves, these locking parts being removed by the agency of duplex finger and thumb clasps located about the middle of the rod. Second, a type in which the curtain rod or stick is of tubular form and in which there are located at the outer ends spring pressed locking devices which are frictionally held in corrugations or grooves of a strip secured in the casings' grooves, the curtain being raised and lowered by grasping "pinch handles" secured to the middle of the rod. Third, a fixture has also been devised in which each of the spring pressed locking devices is provided with a friction pad adapted to bear frictionally against the back of the grooves. It has also been proposed to utilize pairs of spring pressed rollers located at the opposite ends of the curtain rod and adapted to move in corr-

gations or grooves in metal strips in the casings of the window and provided with a finger clip located at the middle of the rod for lifting and lowering the curtain, but none of these types in their perfected forms, as before stated, will accomplish all the results attributable to my improvement which I will now describe, reference being had to the accompanying drawings, in which,

Figure 1 is an elevational view of a car window provided with a spring controlled curtain having my improved fixture attached thereto, the lower corners of the curtain being broken away to better illustrate the details of construction. Fig. 2 is an enlarged view—full sized—of my improved fixture the curtain rod or stick being broken away and the parts segregated so as to give a clear illustration of all of the details of the invention, the left hand end of the rod or stick, the adjustable sleeve, and one of the pivoted parts being shown in sectional view. Fig. 3 is a detail side elevational view as seen looking at Fig. 2 from right to left upon the supposition that the parts shown are detached from the window.

Referring now to the drawings in detail, W represents a car window and C a roller curtain of the spring controlled type, such as are ordinarily used in windows of this nature.

R represents the curtain rod or stick which in this instance is of tubular form and is secured in the lower end of the curtain C in the manner illustrated in Fig. 1. This curtain rod or stick is screw-threaded at its opposite ends for a definite distance for effecting an adjustment of the parts, as will be described more particularly later on, and is provided with a thumb and finger-clip K secured to the rod by a screw, as shown.

S, S represent two sleeves screw-threaded interiorly so as to adapt them to be secured directly to the opposite screw-threaded ends of the rod R. These sleeves are made preferably of brass and are flattened at their outer ends until the interior surfaces come into good mechanical contact with each other. They are then rounded off in the manner shown and a hole is drilled through these flattened portions for the purpose of receiving pivot pins, p, p.

T is a pivoted arm which is constructed of a single folded piece of metal of the conformation shown and having two lateral or side faces and a curvilinear back piece b, together with a short curvilinear bottom piece t, the space between the adjacent parts b and t being sufficient to admit of the insertion of the flattened end of the sleeve S and to also admit of the desired amount of movement of the arm when the fixture is in operation, as will be described later on.

P, P are holding or locking devices of

the conformation shown each pivoted by a pin e in the upper end of the pivoted arm or part T.

s, in this instance, is a leaf spring which is secured at its lower end in a slot in the flattened part of the sleeve S and rests at its upper end, when the parts are assembled, against the long curvilinear side of the second locking devices P. When these parts are assembled in the manner shown the leaf springs are first secured in the grooves in the flattened ends of the sleeves S and the parts T are then pivotally secured in position by the pins p, p. The long ends of the springs s are then forced backward by the insertion of the locking or holding devices P until the pivot pins e can be inserted so as to thus lock the two parts at each end of the rod or stick R into operative relation and so that the long ends of the leaf springs s shall have such a fulcrumed relation around the rounded ends of the flattened portions of the sleeves S as to give proper pressure to the locking devices P, P, when the fixture is ready for use.

N, N represent metal racks having curvilinear teeth the upper faces of which have relatively widely different angular relation, for a purpose to be hereinafter described, said racks being adapted to be held against the casings of the window between two grooved wooden strips G, G by screws or nails, as such devices are usually held. It will be noticed that these metal racks have not the conformation of regular corrugations, but that the faces of the long inclined portions tend to oppose the downward movement of the fixture and bear a definite relation to the corresponding lower longer bearing faces of the pivoted holding or locking devices P; while the other or shorter bearing surfaces of these metal racks are faced downward and bear a corresponding relation to the shorter curvilinear toe-like conformations of the bearing faces of the upper ends of the locking devices P. This difference in angular relation of the upper surfaces of the racks N and the corresponding surfaces of the pivoted or holding devices P constitutes a very essential feature of my invention, in that it is important in the movement of a curtain that when it is drawn downward by grasping the clip K, the resistance which is offered to such downward draft should be a minimum, owing to the fact that when one is moving the curtain downward the resistance of the spiral spring which lifts the curtain upward, when released, is encountered, so that by the combined effect of the long inclined bearing surfaces of the locking devices P and of the metal racks N, I am enabled to offer a minimum angular resistance, and also that when the curtain is moved in the other direction by lifting against the clip K the abrupt ac-

tion of the toes of the devices P against the corresponding abrupt surfaces of the metal racks N will offer sufficient resistance to such upward movement to prevent the curtain from rising too rapidly, under the joint forces. In other words, by this combined relation of pivoted and spring pressed parts having peculiarly designed friction surfaces, together with friction racks having surfaces of a similar nature and interrelated as described, I am enabled to move the curtain in either direction with practically the same amount of applied force, a result which, so far as I am aware, has never before been effected with curtain fixtures of this nature. As a matter of fact this correlation of operative parts is of such a delicate nature that it is not absolutely necessary that one should grasp the clip K to move the curtain in either direction, as I find it may be elevated by applying the hand at any point under the rod or stick R, and may in like manner be drawn down so that when either elevating or lowering the curtain there is not the slightest possibility that one side or the other shall travel the faster, and thereby lock or clamp the same, as so frequently occurs with curtains provided with fixtures of the nature hereinbefore referred to. In fact my novel curtain fixture is, as I have ascertained by practical construction and use, absolutely "self righting" under all conditions of usage and can never be left in such a position in lowering or raising but that it will right itself and assume its correct relation to the window with which it is designed to be used. When it is required to remove the curtain it is only necessary to take hold of the rod or stick at any point and rotate it from left to right a sufficient distance to remove the parts from the slots, and when this occurs the springs S acting upon the locking devices P, P cause the arms or parts T, T to rotate until the bottom pieces t, t bear against the under surfaces of the flattened portions of the sleeves S when the rod or stick may be rotated laterally and the roller part of the curtain detached as desired.

In the event of the casings of the window swelling as they often do, it only becomes necessary to detach the fixture and rotate the sleeves S either in opposite directions or toward each other until the desired adjustment is effected. I have also ascertained, in view of my widely extended knowledge of the use of curtains of this nature in railway cars, that oftentimes the windows are not square or rectangular; that is to say, the casings are not absolutely vertical, so that with existing types of curtain fixtures much annoyance is found to result, owing to the fact that no provision has been made for this type of dissymmetry. My improved curtain fixture absolutely overcomes the sticking or choking of the fixture, no matter what may

be the relation of the casings to the sill; nor to what extent the casings may swell or shrink during different climatic conditions.

I do not limit my invention to the specific details of construction disclosed in the drawings and hereinbefore described, as obviously the structural features thereof might be materially departed from and still come within the scope of my improvement which is directed broadly to the provision of means for effecting the adjustment of a spring controlled curtain as to its position in a window in such manner that by no possibility can it stick; nor can it be broken by careless manipulation; the parts may also be adjusted relatively to each other for effecting all of the results hereinbefore referred to.

Obviously instead of providing adjustable sleeves S with flattened ends constructed as shown for securing the pivoted parts in the manner illustrated and described, such sleeves might be absolutely dispensed with and the ends of the tubular curtain rod or stick R themselves flattened and constructed in the same manner, thereby materially cheapening the structure and minimizing, in so far as possible, the number of parts used, a feature of utility which is very important as to the cost of manufacturing such devices, and my claims are to be construed as of such scope as to include this feature.

Having thus described my invention what I claim and desire to secure by Letters Patent of the United States is—

1. A curtain fixture for a spring actuated curtain, embracing stationary holding means having curvilinear locking faces, the inclinations of the lower faces which incline in opposite directions being more abrupt than the inclinations of the upper faces; together with locking devices and springs for holding said devices against the stationary locking faces of the holding means with sufficient stress to prevent the curtain from being rolled up by its spring, substantially as described.

2. A window curtain fixture having curvilinear holding racks located in the casings of the window, the lower curvilinear faces of the racks being more abrupt than are the upper faces thereof; together with a curtain rod or stick and spring actuated locking devices pivotally secured to the ends thereof, the two bearing faces of the said locking devices corresponding in angular relation with the like bearing faces of the racks, whereby when the curtain is being raised a maximum braking effect is had between the locking devices and the abrupt braking surfaces, and when the curtain is being lowered a minimum braking effect is had between the locking devices and the less abrupt braking faces of the racks, substantially as described.

3. In a curtain fixture two racks having curvilinear teeth the faces of which have relatively widely different angular relation to each other; in combination with a curtain rod or stick and a spring pressed locking device at each end thereof, the frictional faces of the locking devices having a definite angular relation to each other and to the corresponding angular faces of the 10 racks, substantially as described.

4. A curtain fixture embracing racks having curvilinear teeth the frictional faces of which are more abrupt upon the lower side than upon the upper side; in combination 15 with a curtain stick having a holding locking device pivotally secured at each end thereof; each locking device being provided with a spring for forcing it outward into frictional bearing with the teeth of the rack, 20 as the curtain is raised or lowered; the curvilinear faces of the locking devices being respectively angularly related the same as are the frictional faces of the racks, substantially as described.

5. A curtain fixture having a curtain stick secured to the lower end thereof; a pivoted arm or part T at each end; a holding device provided at the free end of each pivoted part, and a spring secured at one end to 30 each pivoted part with its free end resting behind the corresponding holding device; together with two racks having each curvilinear teeth the faces of which differ in angular relation to each other and to the inclined faces of the holding devices, substantially as described.

6. A curtain fixture embracing a curtain rod and pivotally sustained holding devices, one at each end; together with two racks 40 having curvilinear teeth, the frictional faces of which offer relatively widely different resistance to the movement of the curtain rod, dependent upon which direction it is being moved; said holding devices and rod being 45 provided with means for adjusting their operative relations with the racks, substantially as described.

7. A window curtain fixture embracing a tubular curtain rod and tubular sleeves 50 screw-threaded thereon; a pivoted part secured to the outer end of each sleeve, and a locking device pivotally secured to the free end of each pivoted part; in combination with a spring secured to each sleeve and 55 acting each against its corresponding locking device; together with two racks one in each window casing, said racks having curvilinear teeth, the frictional faces of which have relatively widely different angular relation, substantially as described.

8. A curtain fixture embracing a curtain

rod and a pivoted locking device secured to each end of said rod and having movement in a vertical plane in the direction of the length thereof; together with yielding means⁶⁵ for holding each locking device in frictional relation with the window casing, substantially as described.

9. A curtain fixture provided with a curtain rod and two pairs of pivoted arms or parts secured thereto and to each other; together with yielding means for holding one part of each pair frictionally so that the curtain will remain wherever left, substantially as described.

10. A curtain fixture embracing pairs of pivoted parts secured at the lateral edges of the curtain and provided with springs for holding one part of each pair in fixed relation to the window casings, substantially as described.

11. A curtain fixture embracing pairs of locking parts pivotally secured to the opposite ends of a curtain stick and to each other; together with leaf springs for holding the 85 parts in definite relation to each other and to the casings of the window, the structural relation being such that practically the same force is required to either raise or lower the curtain, substantially as described.

12. A window curtain fixture embracing a curtain rod or stick; pairs of locking parts pivotally secured to each other and to the opposite ends of the stick; together with racks having curvilinear teeth and located 95 in the casings of the window; the lower faces of the rack teeth offering more resistance to the holding parts than do the upper faces thereof to the corresponding parts of such holding parts, substantially as described.

13. A window curtain fixture embracing a plurality of frictional locking faces of relatively abrupt curvilinear form, and additional locking faces of relatively less abrupt curvature, all located in the casings of the window; together with locking devices carried by the curtain and having yielding means for holding them in frictional relation with the aforesaid locking faces, the 110 angular relation of said locking devices and the frictional faces being such that practically the same amount of applied force is required to either lower or raise the curtain, substantially as described.

In testimony whereof I have signed my name to this specification in the presence of two subscribing witnesses.
